UNITED STATES PATENT OFFICE.

ERIC J. L. GRANLOW, OF SCHENECTADY, NEW YORK.

DIE STRUCTURE.

Application filed June 3, 1921. Serial No. 474,860.

To all whom it may concern:

Be it known that I, ERIC J. L. GRANLOW, a subject of the King of Sweden, residing at Schenectady, county of Schenectady, State of New York, have invented certain new and useful Improvements in Die Structures, of which the following is a specification.

The present invention relates to dies such as are used with punch presses for punching out or forming small articles from strips or plates of sheet material and has for its object to provide an improved structure and arrangement of dies for performing certain operations to produce articles of a certain type.

For a consideration of what I believe to be novel and my invention, attention is directed to the accompanying description and the claims appended thereto.

In the drawing, Fig. 1 is a vertical, sectional view through upper and lower die structures embodying my invention; Figs. 2 and 3 show successive steps or operations performed by the die structure; Fig. 4 shows a completed article of which the structure shown in Fig. 3 forms an element, and Fig. 5 shows a modified structure of upper die.

One application of my invention is to form an element used in making what is known as the French type of gasket for spark plugs and the invention is particularly illustrated and described in this connection although it is not necessarily limited thereto.

Referring to Fig. 4 of the drawing, it will be seen that a completed gasket comprises a ring 5 of suitable metal such as copper which ring is U-shaped in cross-section, the open side of the U being on the outside of the ring, and held in the groove formed between the two legs of the U is a washer 6 which may be made of asbestos or other suitable material. In forming gaskets of this character a piece of flat stock such as a strip or sheet of copper of suitable thickness is taken and from this strip or sheet a ring is cut and struck or drawn up in the center to form a round cup-shaped member 7 with a flange 8 around its edge as shown in Fig. 2. The end of this cup is then cut out to provide a short cylinder 9 having a flange 10. After the member or

element shown in Fig. 3 has been formed, the washer 6 is placed over cylinder 9 and against flange 10 after which the cylinder 55 is turned out to complete the gasket as shown in Fig. 4.

More particularly the object of my invention is to provide a new and improved die structure which at a single operation 60 will form from flat stock an element as shown in Fig. 3, the die structure first forming a structure as shown in Fig. 2 and then cutting the bottom out of the cup-shaped part 7. This sequence of operations is essential 65 particularly in gaskets of small size since in order to obtain accurate dimensions it is desirable to strike or draw the cup-shaped member before cutting out the bottom.

Referring now to Fig. 1 wherein I have shown my improved die structure, A indicates the lower die structure which is stationary and B the upper die structure which is movable.

The lower die structure comprises a shoe 14 which is adapted to be fastened to the bed plate of a punch press of usual construction. At the center of shoe 14 is a hole 15 counterbored to form a recess 16 in which is located a holder 17 having a central opening 18 counterbored to provide an annular shoulder 19. Projecting from the holder 17 is a threaded flange 20 against the end of which is fixed an outer die member 21, the same being held in place by a flanged nut 22 which threads onto the end of flange 20. Located in the counterbored portion of opening 18 and resting against annular shoulder 19 is a head 23 from which projects an inner die member 24 located centrally of outer die member 21. Inner die member 24 is a solid post and is held in position by a stud 25 which projects down through openings 18 and 15 and has a nut 26 95 on its end which screws up against the bottom of shoe 14. Located in the annular space between die members 21 and 24 is an ejector ring 27 having a head 28 with which engages the upper ends of a number of ejector pins 29, three for example. Ejector pins 29 extend down through openings in holder 17 and shoe 14 and at their lower ends engage a plate 30 against the under side of

which bears the upper ends of a number of springs 31. The lower ends of springs 31 rest on nuts 32 carried by threaded posts 33. Posts 33 are carried by a cross bar 34 supported on the lower ends of rods 34^a which depend from shoe 14. As is obvious, the tension of springs 31 can be adjusted by means of nuts 32 or by means of posts 33. At 33^a are lock nuts for posts 33.

- 10 The upper die structure B comprises a holder 35 adapted to be fastened to the movable jaw of a punch press and provided with an axially extending hole 36. Carried by holder 35 is an inner annular shaped die member 37 having a cutting edge C. Extending through hole 36 is a rod 38 having a head 39 on its lower end which head is located in die member 37. Rod 38 and head 39 form an ejector member and at the center of head 39 is a spring pressed ejector pin 40. The upper end of rod 38 is provided with a washer 41 between which and the end of holder 35 is located a spring 42 which normally holds head 39 above the lower end of die member 37 as shown in Fig. 1. Die member 37 is threaded on its outer surface and screwed thereon is an outer die member 43 provided at its lower end with an inturned flange having a forming surface 44 and a cutting edge 45. Die member 43 is clamped to die member 37 by means of a lock nut 46 and lock washer 47, the nut and die member having co-operating beveled surfaces as indicated at 49
- 35 whereby the outer die member may be firmly gripped to the inner die member. Surrounding die member 43 is a flange 50 having holes 51 through which project loosely pins 52 which support a stripper plate 53. Stripper plate 53 is adapted to slide on outer die member 43.
- 40 A die structure as above described is adapted to form from a flat strip or sheet of material a gasket element as shown in Fig. 3, the same being formed in a single operation as follows:—

45 The upper and lower die structures are placed or mounted in a punch press of usual construction, the lower die structure having its shoe 14 bolted to the bed plate of the press and the holder 35 of the upper die structure being fixed to the reciprocating head or arm of the press. As is well understood, the die structures stand at an angle to the vertical when in the press so the punched out parts will fall by gravity from between them. A strip or piece of sheet material from which the gasket element is to be formed is laid on lower die structure A after which the press brings the upper die structure B against it. Outer die member 43 stands in line with ejector ring 27 and is adapted to pass into the annular space between inner and outer die

members 24 and 21 of the lower die structure. When the die structures come together, a ring is first cut from the sheet material by the outer edge 45 of outer die member 43 and the inner edge of outer die member 21 after which the center of such ring is pressed up into the shape of a cup by inner die member 24 co-operating with the forming surface 44 of die member 43. A structure as shown in Fig. 2 is thus formed. At the end of this forming movement, inner die member 24 passes beyond the lower end of die member 37 with the result that the bottom of the cup-shaped structure is cut out by inner edge C of die member 37 co-operating with the outer edge 80 of inner die member 24. The operation is then complete and as the dies separate, the ejector ring 27 which has been depressed against the action of springs 31 is forced upward again by such springs thus pushing the gasket element as shown in Fig. 3 off inner die member 24 after which it can fall by gravity from between the die structures. As the upper die structure reaches the upper end of its movement, the upper end of rod 36 strikes a stationary part of the press so rod 38 is forced downward to knock the piece which has been cut from the bottom of the cup out of the center of die member 37. The stripper plate 53 serves to knock the sheet of material from which the gasket elements are being formed off the end of die member 43.

50 It will be noted that in the upper die structure B, the outer die member 43 is mounted directly on the inner die member 37 and can be adjusted axially thereon and firmly clamped in adjusted position. This enables the lower end of die member 37 to be very accurately spaced with respect to forming surface 44, and to be adjusted relatively thereto so as to draw cylinders 9 of different heights. This is desirable as it enables the same die to be used for making gaskets of different thicknesses.

55 In connection with the upper die structure it will be seen that the two die members 37 and 43 form in substance a single die element or means adapted to enter the annular space between lower die members 21 and 24 and that such die element or means presents an outer cutting edge which co-operates with the cutting edge of die member 21, a curved forming surface 44, and an inner cutting edge which is spaced beyond or behind the outer cutting edge and the forming surface 44 and co-operates with the cutting edge of inner die member 24.

60 It will be understood that in use the operation is continuous as in any punch press and that each time the dies come together, they form a complete gasket element as shown in Fig. 3.

In Fig. 5, I have shown a modified form of upper die structure which in many respects is similar to that shown in Fig. 1 and corresponding reference numerals with the 5 exponent a added are used to designate corresponding parts. In the Fig. 5 arrangement, the inner die member 37 a is formed separate from holder 35 a , instead of integral therewith as in Fig. 1, and is fastened thereto by a set screw 60. This arrangement enables the die member to be renewed without making a new holder also. The 10 outer die member 43 a threads into holder 35 a as indicated at 61 and by turning the holder 15 and outer die member relatively to each other the distance between the cutting edge of inner die member 37 a , i.e., its lower end, and the lower end of outer die member 43 a can be accurately adjusted. Holder 35 a is 20 split longitudinally as shown at 62 and when the holder is clamped in the punch press outer die member 43 a will be tightly gripped in the holder and held in its correct, adjusted position. In this arrangement flange 25 50 a which carries stripper plate 53 a is formed separate from die member 43 a and is fastened in place by a set screw 63. Surrounding pins 52 a of which there may be three, for example, equally spaced, are 30 springs 64 which act to hold the stripper plate in the position shown in the drawing and assist in returning it to such position when during the operation of the die it is pushed up on die member 43 a . In Fig. 35 1 the stripper plate 53 is returned by its weight alone while in Fig. 5 the stripper plate 53 a is returned by its weight assisted by springs 64.

The operation of die member as shown in 40 Fig. 5 is the same as that of Fig. 1. The die structure itself however is somewhat simpler and has the advantage that the die members 37 a and 43 a can be renewed more easily and cheaply.

45 It will be understood that a die structure embodying my invention may be used to provide elements of shapes other than that shown in Fig. 3 by varying the shape or arrangement of the forming surfaces.

50 In accordance with the provisions of the patent statutes, I have described the principle of operation of my invention, together with the apparatus which I now consider to represent the best embodiment thereof, but 55 I desire to have is understood that the apparatus shown is only illustrative and that the invention may be carried out by other means.

What I claim as new and desire to secure by Letters Patent of the United States, is:— 60

1. In combination, a die structure comprising two spaced concentric die members and a second die structure having two concentric die members one of which has a forming surface and the other a cutting edge 65 located behind said forming surface, said die members co-operating to first strike up a cup-shaped protuberance from a sheet of material and then cut the bottom from the protuberance. 70

2. In combination, a die structure comprising two spaced concentric die members and a second die structure having die means which is adapted to enter the annular space between the two spaced die members, said 75 die means having an outer cutting edge, a forming surface and an inner cutting edge spaced beyond said forming surface in an axial direction.

3. In combination, a die structure which 80 presents two spaced concentric cutting edges and a second die structure having a part adapted to pass between spaced cutting edges and having cutting edges for co-operation therewith, the cutting edges on said part being spaced one axially beyond the other, said die structures having co-operating forming surfaces. 85

4. In a die structure, a die element having an outer cutting edge, a forming surface 90 which extends axially beyond said cutting edge, and an inner cutting edge located axially beyond said forming surface.

5. In a die structure, an inner die member having an inner cutting edge and an outer 95 die member fixed on the inner die member and having an outer cutting edge and a forming surface both in advance of the inner die member as regards the movement of the die structure. 100

6. In a die structure, an inner die member having an inner cutting edge, an outer die member adjustable axially with respect to the inner die member, said outer die member having a cutting edge and a 105 forming surface, and means for locking said die members in fixed position relatively to each other.

In witness whereof, I have hereunto set my hand this 31st day of May, 1921.

ERIC J. L. GRANLOW.

In presence of:—
Wm. A. FRIEDMAN.
